DESIGN FOR A BUTTON

Ellerton M. Jetté, Waterville, Maine, assignor to
Theodore G. Robinson, New York, N. Y.

Application October 8, 1937, Serial No. 72,082

Term of patent 14 years

To all whom it may concern:

Be it known that I, Ellerton M. Jetté, a citizen of the United States of America, residing in Waterville, county of Kennebec, and State of Maine, have invented a new, original, and ornamental Design for Buttons, of which the following is a specification, reference being had to the accompanying drawing, forming part thereof.

Figure 1 is a perspective view of the button showing my new design;

Figure 2 is a plan view of same; and

Figure 3 is a sectional view taken on the line 3—3 of Fig. 2.

The button shown in the drawing and embody-

ing my design consists of a circular button having a concave face. The concave face has a substantially sharp arc-shaped slope from the outer edge of the button and flattens out to form a slightly defined, flat-bottomed, central surface. The central surface has three circular holes which have walls perpendicular to its horizontal plane. My invention embraces a button having substantially these novel features.

I claim:

The ornamental design for a button, substantially as shown and described.

ELLERTON M. JETTÉ.
